UNITED STATES PATENT OFFICE

150,306

DESIGN FOR A DRIP PAN FOR WATER CLOSET TANKS

Virgil E. Laufenberg, Milwaukee, Wis., assignor to Laufenberg, Inc., Milwaukee, Wis., a corporation of Wisconsin

Application May 8, 1948, Serial No. 146,240

Term of patent 14 years

(Cl. D4—3)

To all whom it may concern:

Be it known that I, Virgil E. Laufenberg, a citizen of the United States, residing at Milwaukee, in the county of Milwaukee and State of Wisconsin, have invented a new, original, and ornamental Design for a Drip Pan for Water Closet Tanks, of which the following is a specification, reference being had to the accompanying drawing, which forms a part thereof.

And Figure 5 is a perspective view of the drip pan showing the same in its attached relation to a water closet flush tank, the latter being shown in broken lines.

The dominant features of my design are shown in solid lines.

I claim:

The ornamental design for a drip pan for water closet tanks, as shown and described.

VIRGIL E. LAUFENBERG.
